UNITED STATES PATENT OFFICE.

GEORG BECKH, OF NUEREMBERG, GERMANY.

JUMPING-ROPE.

SPECIFICATION forming part of Letters Patent No. 623,698, dated April 25, 1899.

Application filed December 29, 1898. Serial No. 700,595. (No model.)

To all whom it may concern:

Be it known that I, GEORG BECKH, a citizen of the German Empire, residing at Nuremberg, in the Kingdom of Bavaria and Empire of 5 Germany, have invented certain new and useful Improvements in Jumping-Ropes, of which the following is a specification.

This invention relates to a jumping-rope for the use of children; and the object of the same 10 is to provide a jumping-rope which is attractive, unique, durable, and imponderable.

The invention consists, broadly, of a jumping-rope which comprises a pair of handles, a cord connecting the same, and a covering 15 of helically-wound strands of tinsel upon said connecting-cord.

The invention consists, further, of a plurality of tinsel-covered cords twisted together and connecting the handles; and the invention 20 consists, lastly, of larger and extra or additional outer coverings of helically-wound strands of tinsel arranged upon the mid-length of the jumping-rope, so as to make that part heavier.

25 In the accompanying drawings, Figure 1 is an elevation of my improved jumping-rope. Fig. 2 is an enlarged longitudinal section through a handle and adjacent part of the rope. Fig. 3 is a transverse section on line 30 3 3, Fig. 2; and Fig. 4 is an enlarged section through the middle portion of the rope on line 4 4, Fig. 1.

Referring to the drawings, A A' indicate the axially-bored handles of suitable shape, 35 and B B' the cords which connect the handles and which are secured therein by tying a knot on the ends of the cords, such knot being covered by a cap *a*, screwed onto the handles. The cords B B' are wound tightly with small 40 wire C of light weight, and then upon these wire-wound cords helically-coiled tinsel wire or strands D D' are arranged so as to practically cover the cords. The ends of the tinsel-strands D pass into metallic cups or bell- 45 shaped tips D, which are strung on the connecting-cords adjacent to the handles. Between the coiled strands of tinsel D and upon the mid-length of the connecting-cords are

placed other or additional coverings E E' of helically-wound tinsel wire or strands. These 50 are of greater diameter than the tinsel coverings D, so as to make the rope larger at the mid-length and to inclose the inner ends of the coverings D. Also these tinsel coverings E make the rope somewhat heavier at its mid- 55 length, so that the child can jump the better. Before fastening the ends of the connecting-cords into the handles the same, with their tinsel coverings, are twisted, so as to hold together and to impart a decidedly ornamental 60 appearance to the jumping-rope. The strands of tinsel can be of various colors, so as to make the jumping-rope attractive, which, taken with the glittering and handsome appearance of the tinsel, strikes the fancy of children and 65 renders the device a salable article, much sought after.

Having thus described my invention, what I claim as new, and desire to secure by Letters Patent, is—

70 1. A jumping-rope, consisting of a pair of handles, a connecting-cord, small helically-wound strands of tinsel, extending from the handles toward the middle portion of and wound around the cord, and an additional or 75 separate covering-strand of tinsel upon the middle portion of said cord, said covering-strand being of greater diameter than the other strands, and inclosing the ends of the same, substantially as set forth. 80

2. A jumping-rope, consisting of a pair of handles, connecting-cords, small helically-wound strands of tinsel, wound separately around each cord, and twisted together, and additional or separate covering-strands of tinsel upon the twisted middle portion of the cords, said covering-strands being each of greater diameter than and inclosing the ends of the other strands, substantially as set forth. 85

In testimony that I claim the foregoing as 90 my invention I have signed my name in presence of two subscribing witnesses.

GEORG BECKH.
